UNITED STATES PATENT OFFICE.

FRANK J. HUSBANDS, OF LOS ANGELES, CALIFORNIA, ASSIGNOR, BY MESNE ASSIGNMENTS, TO ACME TRAFFIC SIGNAL COMPANY, A CORPORATION OF CALIFORNIA.

AUTOMATIC TRAFFIC REGULATOR.

Application filed April 20, 1920. Serial No. 375,374.

To all whom it may concern:

Be it known that I, FRANK J. HUSBANDS, a citizen of the United States, residing at Los Angeles, in the county of Los Angeles 5 and State of California, have invented new and useful Improvements in Automatic Traffic Regulators, of which the following is a specification.

This invention is a traffic regulator providing a signal at points of traffic intersection, the signals for the respective points of traffic intersection being either independently locally controlled or simultaneously controlled from a central station, and 10 the central station controlling means being arranged to automatically give a signal for movement of traffic in the respective cross directions at the points of traffic intersection at regular intervals.

20 It is the object of the invention to provide a traffic regulator of this character having means for selectively giving a signal for movement of traffic in all directions at a point of traffic intersection, for giving a signal to stop traffic in all directions at said point, or for giving a signal for movement of traffic in one of the cross directions at said point and for stopping the traffic in the other direction at said point, the selective 25 controlling means being either independently locally actuated at the respective points of traffic intersection or automatically actuated from a central station.

In practice it has been found necessary 30 that the traffic regulator operate to give a signal for movement of traffic in all directions at a point of traffic intersection during certain periods and particularly at night when the traffic is practically negligible. 35 Further, it is also necessary to provide a traffic regulator for giving a signal to stop traffic in all directions at a point of intersection in order to prevent movement of traffic when an ambulance or similar form of emergency vehicle is traversing the 40 streets.

Other objects of the invention will be 45 readily understood from the following description of the accompanying drawings in which;

Figure 1 is a front elevation of one of the signalling units partly broken away.

Fig. 2 is a longitudinal section through the same taken on the line 2—2 of Fig. 1.

Fig. 3 is a transverse section on the line 55 3—3 of Fig. 2.

Fig. 4 is a diagrammatic showing of several points of traffic intersection such as intersecting streets, units of the improved traffic regulator being positioned at the 60 points of traffic intersection.

Fig. 5 is an enlarged plan view of the automatic controlling means employed in the traffic regulator.

Fig. 6 is a transverse section on the line 65 6—6 of Fig. 5.

Fig. 7 is a diagrammatic showing of the traffic regulating system.

Fig. 8 is a similar showing of the local controlling means for the traffic regulator 70 with the units of the regulator in opposite signalling position to that shown in Fig. 7.

Figs. 9 and 10 are diagrammatic showings of a traffic regulator and its local controlling means showing different controlling 75 positions of the controlling means.

Figs. 11, 12, 13 and 14 are diagrammatic showings of a traffic regulator and the central station controlling means therefor, said controlling means being shown in the various controlling positions.

The improved traffic regulator is illustrated as employed in connection with points of traffic intersection as shown in Fig. 4 in which parallel streets or roads are shown at A and parallel cross streets or roads are shown at B. One of the signalling units of the traffic regulator is positioned at each corner of the intersecting streets A and B, each of these signalling units being provided with semaphore arms adapted to be selectively projected into signalling position so as to be seen when moving along either of the cross streets A and B in the normal direction of traffic movement.

In the drawings two streets are shown intersecting in each instance, thereby forming four corners necessitating the employment of four of the signal units at each intersection. It will be obvious, however, that when more than two streets intersect at a common point more than four corners will be provided thereby necessitating the employment of more than four of the signal units at each intersection. In each case a signal unit is provided upon each corner irrespective of the number of corners at the intersection, each of these signal units being adapted to

control traffic along the street at the side of the corner along which traffic naturally moves in a direction toward the signal unit.

The respective signal units comprise a casing 1 mounted upon a suitable base 2. Shafts 3 and 4 longitudinally aligned are journaled in the casing 1, preferably, in a bracket 5 having the bearing arms 6. The opposite side walls of the casing 1 are, preferably, provided with inner spaced walls 7, and the bearing bracket 5 may have its bearing ends 6 suitably secured to these inner spaced walls. The shafts 3 and 4 are journaled in the bearings 6 and extend through the respective walls 7, suitable semaphore arms 8 being secured upon the respective shafts at right angles to one another, so that when the shafts are simultaneously rocked one of said semaphore arms will be in vertical position within the casing of the signal unit, and the other semaphore arm will be in horizontal position projecting outwardly from the casing of the signal unit, the said casing being provided with suitable slots 9 through which the semaphore arms may be thus projected.

Rock arms 10 project laterally from opposite sides of the shafts 3 and 4, these rock arms being shown as fixed relative to the shafts by collars 11, preferably, integral with the respective rock arms and fixed upon the respective shafts 3 and 4. Operating rods 12 are pivotally connected to the ends of the rock arms 10, as shown at 13, the parts being so arranged that longitudinal movement of the operating rods within the casing of the signal unit in reverse directions will reversely rock shafts 3 and 4 to project one or the other of the semaphore arms 8 outwardly into signalling position while the other of the semaphore arms is concealed within the casing 1. These semaphore arms are adapted to signal for traffic movement and for stopping of traffic movement respectively, and for this purpose may have the words "Go" and "Stop" on the respective arms.

The operating rods 12 are adapted to be reciprocated within the casing 1 by a suitable electro-magnet formed as a solenoid comprising upper and lower sections 14 and 15, the movable core of said solenoid being shown at 16. The operating connection between the core 16 and the operating rods 12 may comprise a rod 17 extending upwardly from the core 16 and, preferably, having a sliding bearing 18 in the bearing bracket 5, the operating rods 12 being secured to the rod 17 by a yoke 19 fastened upon the rod 17 and having the ends of the operating rods 12 pivoted thereto as shown at 20.

When the core of the solenoid is at either end of the solenoid and the opposite end section thereof is energized, the core will be moved within the solenoid to a position

within said energized end of the solenoid and the operating rods will accordingly be moved longitudinally within the casing 1 to rock the shafts 3 and 4 to change one of the semaphore arms from signalling position and to display the other semaphore arm in signalling position. The shafts 3 and 4 and the operating connections therefor are so arranged that when the shafts are rocked, the rock arms 10 will be moved from a point at one side of the axis of the shafts 3 and 4 to a point at the opposite side of said axis, the rock arms being, preferably, yieldably held in either one of these positions by a spring 21 connecting the operating rods 12. By this construction it will be seen that when the shafts 3 and 4 have been rocked to display one of the semaphore arms the parts will remain in the same position until the solenoid is energized to rock the shafts 3 and 4 in the reverse direction for displaying the other semaphore arm.

One of the semaphore arms of a signal unit is, preferably, provided with a contact arm 22 arranged to close an electrical circuit through either a contact 23 or a contact 24 depending upon whether said semaphore arm is in signalling position or in concealed position. The contact arm 22 is shown as carried by the "Go" semaphore arm and as closing a circuit through the contact 23 when in signalling position and as closing a circuit through contact 24 when in concealed position. The electrical circuits thus formed are for circuits through electrical lamps 25 and 26 respectively.

These lamps are shown as carried upon the signal unit, preferably, in a casing 27 in the front of the casing of the unit, this casing being provided with windows through which the lamps are adapted to show. The windows are shown at 28 and 29 and are, preferably, of different colored glass, as for example a yellow glass in the window 29 for the lamp 26 which is arranged to be illuminated when the "Go" signal is shown, and a red glass in the window 28 for the lamp 25 which is illuminated when the "Stop" signal is shown.

Suitable electrical circuits, to be herein-after described, are provided through the respective lamps 25 and 26, and through the respective contacts 24 and 23, and through the contact arm 22 of the "Go" semaphore arm, so arranged that when the "Go" signal is shown the circuit through contact 23 will be closed to illuminate the lamp 26, and when the "Go" signal is in concealed position and the "stop" signal is shown the circuit through the contact 24 will be closed to illuminate lamp 25.

An audible signal shown as a bell 30 is, preferably, provided in the casing 1 of the signal unit, this bell being shown as an electrical bell in an electrical circuit, to be here-

inafter described, which passes through the upper section 14 of the actuating solenoid, so that when this circuit is closed and the upper section of the solenoid is energized to display the "Stop" signal, the bell will be sounded.

The signal units at the corners of a point of traffic intersection are arranged to be either locally controlled from the point of traffic intersection, or the signal units at several points of traffic intersection may be simultaneously controlled from a central station. Furthermore, the signal units at one point of traffic intersection may be selectively actuated so that all of the units are in "Go" signalling position, or so that all of the units are in "Stop" signalling position, or so that the units controlling traffic in one of the cross directions of traffic are in one of the signalling positions, and the units controlling traffic in the cross direction of traffic are in the opposite signalling position. When the signalling units are in this latter position, controlling means are also provided for simultaneously reversing the signalling positions of the units. These controlling means are, preferably, electrically controlled, the electrical circuits and switches being diagrammatically illustrated in Figs. 7 to 14.

In Fig. 7 the circuits and controlling means for the signal units, at a plurality of points of traffic intersection either locally controlled or controlled from a central station, are illustrated, one set of electrical circuits passing through the upper sections 14 of the actuating solenoids of the signalling units for energizing the upper sections of the actuating solenoids to cause the "Stop" signal to be displayed, and a second set of electrical circuits passing through the lower sections 15 of the solenoids to cause the "Go" signals to be displayed.

For the purpose of illustration, four signal units are shown at the point of traffic intersection, the units 31 and 33 controlling traffic in opposite directions along one street, and the units 32 and 34 controlling traffic in opposite directions along the intersecting street. In Fig. 7 these signal units are shown with the units 31 and 33 in "Go" position to permit traffic movement along one of the intersecting streets and the units 32 and 34 in "Stop" position to prevent traffic along the intersecting street.

The local controlling means for the signal units is shown as comprising a switch 35 having the contact arms 36 and 37 arranged to be thrown from the position shown in Figs. 7 and 8 to that shown in Figs. 9 and 10. The arm 36 of this switch, when in the position shown in Figs. 7 and 8, closes circuits through contacts 38, 39^a, 39^b and 39^c, and the arm 37 of the switch closes circuits through the contacts 39, 38^a, 39^b and 38^c.

An electrical connection is provided from one side of a source of electrical energy represented at 50, which may be the usual city lighting system through the wire 40 and the branch wires 41 and 42 to the arms 36 and 37 respectively of the switch 35. Switches 43 and 44 are provided in the branch wires 41 and 42 respectively, so that when one of said switches is closed and the other switch is open, current will be supplied to one of the arms of switch 35, and when the other of the switches in the branch wires 41 and 42 is closed and the first mentioned of said switches is opened, current will be supplied to the other arm of the switch 35.

The contacts 38, 38^a, 38^b and 38^c are electrically connected to the upper end of the sections 14 of the respective solenoids of the signal units 31, 32, 33 and 34 as by the wires 45, 45^a, 45^b and 45^c respectively, and the contacts 39, 39^a, 39^b and 39^c are electrically connected to the lower end of the sections 15 of the solenoids of the signal units 31, 32, 33 and 34 as by wires 46, 46^a, 46^b and 46^c respectively. The adjacent ends of the sections 14 and 15 of the respective actuating solenoids of the respective signal units 31, 32, 33 and 34 are electrically connected by wires 47, 47^a, 47^b and 47^c respectively, these wires being connected in a common wire 48 leading to the opposite side of the source of electrical energy 50.

When it is desired to set the signal units in the position shown in Fig. 7, the switch 35 is thrown to the position shown in this figure with the arms 36 and 37 closing their respective contacts. The switch 44 is closed and circuits are thereby formed through the lower sections 15 of the actuating solenoids of the signal units 31 and 33 and through the upper sections 14 of the actuating solenoids 32 and 34 to set the respective signal units in the position "Go" or "Stop" as shown in Fig. 7. The circuits through these respective sections of the solenoids may be traced as follows: from the source of electrical energy 50, through wire 40, wire 42, switch 44, (the switch 43 in the opposite branch wire 41 from wire 40 being open) through switch arm 37 and contacts 39, 38^a, 39^b and 38^c and wires 46, 45^a, 46^b and 45^c respectively, through the lower section 15 of the solenoid of the signal unit 31, through the upper section of the solenoid of unit 32, through the lower section of the solenoid of unit 33, and through the upper section of the solenoid of unit 34 respectively, through the respective branch wires 47, 47^a, 47^b and 47^c to the connecting wire 48, and thence to the opposite side of the source of electrical energy 50.

When the switch 44 is closed, thus closing the circuits as above traced, the signal arms of the respective signal units will be moved

to the positions shown in Fig. 7 and the signal arms will be held in these positions until the opposite ends of the respective solenoids are energized by the construction 5 of the operating rods 12 and the spring 21, as previously described. It is therefore, only necessary to close the switch 44 momentarily, the circuits closed by this switch being opened by opening the switch as soon as 10 the signal arms have been moved to their various positions.

After the signal units have been set in the position shown in Fig. 7 and traffic at a point of intersection has moved in one of 15 the cross directions and has been stopped in the other cross direction, the opposite signal arm of the respective signal units is adapted to be shown so as to permit movement of traffic and holding of traffic in the opposite 20 cross directions. The respective signal units set in this position are shown in Fig. 8, the unit 31 being changed from "Stop" position to "Go" position and the remaining units having their signals similarly 25 reversed. This reversing of the respective signals is accomplished by energizing the ends of the actuating solenoids opposite the ends previously energized so as to rock the respective shafts 3 and 4. For this purpose 30 the switch 35 is allowed to remain in the same position and the switch 44 is left open and the switch 43 is momentarily closed thereby forming the following circuits through the respective actuating solenoids 35 as shown in Fig. 8.

From the source of electrical energy 50, through the line 40, the branch line 41, (the switch 43 being closed) through the arm 36, the contacts 38, 39^a, 38^b and 39^c respectively to the lines 45, 46^a, 45^b and 46^c, and thence through the upper sections 14 of the actuating solenoids of the signal units 31 and 33, and through the lower sections 15 of the actuating solenoid of signal 45 units 32 and 34 to the wires 47, 47^a, 47^b and 47^c, and thence through the wire 48 to the opposite side of the source of electrical energy.

The bells 30 of the respective signal units 50 are arranged to be sounded when the "Stop" signals are shown, and for this purpose each bell is shown as shunted across the circuit through the upper section 14 of the actuating solenoid. The connections for the bell 55 being shown as a wire 51 from the respective wires 45, 45^a, 45^b and 45^c to one side of the bell, and a wire 52 from the opposite side of the bell to the branch wires 47, 47^a, 47^b and 47^c.

60 The circuits for the lamps 25 and 26 are formed through the contacts 24 and 23 respectively, as previously described, these circuits, preferably, comprising a wire 53 from the respective branch wires 47, 47^a, 47^b and 47^c having branch wires 54 and 55 con-

nected to one side of the respective lamps 26 and 25, a wire 56 leading from the opposite side of the lamp 26 to the contact 23, and a wire 57 leading from the opposite side of the lamp 25 to the contact 24. The contact arms 22 of the "Go" semaphore arms are each connected to the wire 40 leading to the source of electrical energy as by branch wires 58, 58^a, 58^b and 58^c leading from the respective contact arms and connected by 75 a common wire 59 to the wire 40, a switch 60 being, preferably, provided in the wire 59 for throwing the electrical lamps into or out of operation.

By referring to Fig. 7 it will be seen that 80 when the "Go" signal is shown the lamp 26 will be illuminated, the circuit through one of these lamps, say the lamp of the signal unit 31, being traced from the wire 48, wire 47, through wire 53, wire 54, the lamp 26, wire 56, contact 23, contact arm 22 and wire 58 to the wire 59, through the closed switch 60 and thence to the wire 40. When the "Stop" signal of a unit is set the lamp 25 will be illuminated, the circuit through one 85 of these lamps, say the lamp of the signal unit 32, being traced from wire 48, wire 47^a, through wire 53, wire 55, the lamp 25, wire 57, contact 24, contact arm 22, the wire 58^a and thence to the wire 59 through the closed 90 switch 60 to the wire 40.

The local switch 35 is also arranged to control means for causing all of the signals at the point of traffic intersection to be set at "Go", or all of the signals to be set at "Stop". For this purpose the switch 35 is arranged to be thrown from the position shown in Figs. 7 and 8 to the position shown in Figs. 9 and 10, the arm 36 of the switch in this latter position making contact with contacts 61, 61^a, 61^b and 61^c, and the arm 37 of the switch making contact with contacts 62, 62^a, 62^b and 62^c. The contacts 61, 61^a, 61^b and 61^c are connected to the wires 45, 45^a, 45^b and 45^c respectively, and the contacts 62, 62^a, 62^b, and 62^c are connected to the wires 46, 46^a, 46^b and 46^c respectively, as by wires 63, 63^a, 63^b and 63^c and wires 64, 64^a, 64^b and 64^c respectively.

Referring, now, to Fig. 9 it will be seen 115 that when the switch 44 is closed (the switch 43 being open) circuits will be formed through the respective lower sections of the actuating solenoids to set the respective signals in "Go" position, these circuits being traced from the source of electrical energy 50 through the switch 44, previously described, and thence through the arm 37, through the contacts 62, 62^a, 62^b and 62^c, wires 64, 64^a, 64^b and 64^c, wires 46, 46^a, 46^b and 46^c, and thence through the respective sections 120 15 of the actuating solenoids and back to the source of electrical energy, as previously described.

When it is desired to set all of the signal 130

units in "Go" position the switch 43 is closed (the switch 44 being open) and the circuits through the respective upper sections 14 of the actuating solenoids may be traced as follows, reference being had to Fig. 10: from the source of electrical energy 50, through the switch 43, as previously described, through the arm 36 and through the respective contacts 61, 61^a, 61^b and 61^c to the respective wires 63, 63^a, 63^b and 63^c to the respective wires 45, 45^a, 45^b and 45^c, and thence through the respective sections 14 of the actuating solenoids and back to the source of electrical energy 50, as previously described. By this arrangement the respective signal arms will be moved to "Stop" position, as previously described.

The central station controlling means for the traffic regulators, preferably, comprises means whereby one series of the traffic regulators at various points of traffic intersection may be simultaneously controlled and another series of the regulators may be separately simultaneously controlled. For example all of the traffic regulators at the point of traffic intersection along one of the streets A in Fig. 4 may be simultaneously controlled and all of the regulators along another of the streets A may be separately simultaneously controlled. In the following description the controlling means for the traffic regulator at one point of traffic intersection will be first described, and the means whereby a plurality of such regulators along one of the streets A may be simultaneously controlled, will then be described.

Referring to Fig. 7, a controlling switch 66, 66^a, 66^b and 66^c is provided in the circuit to the respective signal units 31, 32, 33 and 34, these switches being controlled by either a switch 80 in the central station or a switch 105 or 106 therein, the switch 80 being employed when it is desired to set the signal units in opposite signalling positions for the cross directions of traffic, as shown in Figs. 7 and 8, and the switches 105 and 106 being employed when it is desired to set all of the signal units in "Go" and "Stop" positions respectively.

As an instance of this arrangement, the switches 66, 66^a, 66^b and 66^c are shown as comprising electro-magnets 70, 70^a, 70^b and 70^c and 71, 71^a, 71^b and 71^c having the swinging contact arm 72, 72^a, 72^b and 72^c arranged between the magnets and adapted to be swung toward one or the other of the magnets to close the contacts 73, 73^a, 73^b and 73^c and 74, 74^a, 74^b and 74^c respectively when the magnets 70, 70^a, 70^b and 70^c and 71, 71^a, 71^b and 71^c are respectively energized. The contacts 73, 73^a, 73^b and 73^c of the respective switches 66, 66^a, 66^b and 66^c are connected to the wires 46, 46^a, 46^b and 46^c of the circuits through the sections 15 of the actuating solenoids, previously described, as by wires 75, 75^a, 75^b and 75^c, and the contacts 74, 74^a, 74^b and 74^c of the respective switches are connected as by wires 76, 76^a, 76^b and 76^c to the wires 45, 45^a, 45^b and 45^c of the circuits through the upper sections 14 of the actuating solenoids, previously described. The swinging contact arms 72, 72^a, 72^b and 72^c of the respective switches are connected by a wire 77 to the wire 40 leading from the source of electrical energy 50, as previously described, a switch 78 being provided in the wire 77.

When it is desired to control the signal units of a traffic regulator from the central station, the switch 78 is closed and, by means to be hereinafter described, the swinging contact arms 72, 72^a, 72^b and 72^c of the switches 66, 66^a, 66^b and 66^c are thrown to make contact with either the contact points 73, 73^a, 73^b and 73^c or 74, 74^a, 74^b and 74^c. When it is desired to set the signal units in the position shown in Fig. 7, that is with the units 31 and 33 in the "Go" position and the units 32 and 34 in the "Stop" position, the controlling means for the switches 66, 66^a, 66^b and 66^c will be actuated to energize the magnets 70, 71^a, 70^b and 71^c thereby swinging the contact arms 72, 72^a, 72^b and 72^c so as to make contact with the contacts 73, 74^a, 73^b and 74^c, as shown in Fig. 12.

Referring to Fig. 12 the circuits to the respective solenoids of the signal units may be traced as follows: from the source of electrical energy 50, through wire 40 to wire 77, (switch 78 being closed) through the respective contact arms 72, 72^a, 72^b and 72^c, through contacts 73, 74^a, 73^b and 74^c, through the wires 46, 45^a, 46^b and 45^c and through the lower sections of the solenoids of the signal units 31 and 33 and through the upper sections of the solenoids of the signal units 32 and 34, as previously described, and thence back to the source of electrical energy 50.

When it is desired to reverse the signalling position of each of the signal units, as shown in Fig. 8, the central station controlling means will actuate the magnets 71, 70^a, 71^b and 70^c of the respective switches 66, 66^a, 66^b and 66^c to throw the contact arms 72, 72^a, 72^b and 72^c to the positions shown in Fig. 11 for closing the circuits through the upper portions 14 of the solenoids of the signal units 31 and 33, and for closing the circuits through the lower sections 15 of the solenoids of the signal units 32 and 34. The circuits through the respective solenoids will then be as follows, reference being had to Fig. 11: from the source of electrical energy 50, through wires 40 and 77, (switch 78 being closed) through the respective contact arms to contacts 74, 73^a, 74^b and 73^c, respectively and thence through wires 45,

46^a, 45^b and 46^c to the sections of the respective solenoids connected therewith, and thence back to the source of electrical energy 50.

5 When, now, it is desired to set all of the sets of a signal at "Stop" position or at "Go" position from the central station the switch 78 is closed and either the magnets 71, 71^a, 71^b and 71^c are energized or the magnets 70, 70^a, 70^b and 70^c are energized, thereby either closing the contacts 74, 74^a, 74^b and 74^c to actuate the upper sections 14 of the solenoids of the unit or closing the contacts 73, 73^a, 73^b and 73^c to energize the sections 15 of the solenoids. All of the units of a signal are thus set in either "Go" or "Stop" position, the circuits through the solenoids being traced as follows: from the source of electrical energy 50, through wires 40 and 77, (switch 78 being closed) and through the contact arms 72, 72^a, 72^b and 72^c to either the contacts 74, 74^a, 74^b and 74^c, wires 76, 76^a, 76^b and 76^c, wires 45, 45^a, 45^b and 45^c and through the upper sections 14 of the solenoids, or through contacts 73, 73^a, 73^b and 73^c, wires 75, 75^a, 75^b and 75^c, wires 46, 46^a, 46^b and 46^c, through the lower sections 15 of the solenoids, to set the signals in either "Stop" or "Go" position and thence 30 in either case through the wires 47, 47^a, 47^b and 47^c to wire 48 and back to the source of electrical energy.

The central station controlling means for the electro-magnets, above described, may 35 comprise a switch 80 having the arms 81 and 82. When this switch is in closed position the arm 81 makes contact with contacts 83, 84^a, 83^b and 84^c and the arm 82 makes contact with the contacts 84, 83^a, 84^b and 83^c. The contacts 83, 83^a, 83^b and 83^c are connected respectively to one of the terminals of the magnets 70, 70^a, 70^b and 70^c as by wires 85, 85^a, 85^b and 85^c, and the contacts 84, 84^a, 84^b and 84^c are connected respectively to one of the terminals of the magnets 71, 71^a, 71^b and 71^c as by wires 86, 86^a, 86^b and 86^c.

A source of electrical energy, preferably, a low voltage generator 87 is provided in the central station, this generator being connected through a wire 88 with the opposite terminals of the magnets 71, 71^a, 71^b and 71^c as through a branch wire 89 having the connecting wires 90, 90^a, 90^b and 90^c to said 55 respective magnets, the wire also having connection to the opposite terminals of the respective magnets 70, 70^a, 70^b and 70^c as through connecting wires 91, 91^a, 91^b and 91^c. The opposite side of the generator 87 is connected to an automatic two-way switch 92 as by a wire 100, this switch having the contacts 93 and 94 arranged respectively to alternately make and break contact with the contacts 95 and 96. The contact 95 is con-

nected to the arm 81 of switch 80 as by a wire 97 and the contact 96 is connected to the other arm 82 of this switch as by a wire 98.

When it is desired to automatically energize at regular intervals either the magnets 70, 71^a, 70^b and 71^c, or the magnets 71, 70^a, 71^b and 70^c to set the signals for one direction of cross traffic at "Go" and the signals for the other direction of cross traffic at "Stop" and then to reverse the respective signals, as previously described, and as diagrammatically illustrated in Figs. 11 and 12, the automatic switch 92 is rotated so as to first make connection between wire 100 and contact 96, as shown in Fig. 11, and then to break this contact and make connection between wire 100 and contact 95.

For this purpose the rotary switch 92 may comprise rotatable members 101 and 102 fixed upon a shaft 103 and having the diametrically oppositely arranged electrical contacts 93 and 94 upon the respective rotatable members, as is clearly shown in Figs. 5 and 6. The contacts 95 and 96 engaged respectively by the contacts 93 and 94 may be carried upon suitable arms so arranged that the contacts 93 and 94 will have wiping contact with the respective contacts 95 and 96. The shaft 103 may be rotated at the desired speed through a suitable reduction gearing 104 from an electric motor 104^a deriving its energy from any suitable source of power.

The reduction gearing is, preferably, so arranged as to make and break the contacts at, say approximately minute intervals, so that the signal units will be actuated to alternate the directions of cross traffic at minute intervals.

When the switch 92 is in the position 105 illustrated in Fig. 11 the circuits through the controlling magnets for contact arms 72, 72^a, 72^b and 72^c will be as follows: from the generator 87, through wire 100, through switch 92, contact 94, contact 96, wire 98, switch arm 82, contacts 84, 83^a, 84^b and 83^c, through wires 86, 85^a, 86^b and 85^c, through magnets 71, 70^a, 71^b and 70^c and thence through wires 90, 91^a, 90^b and 91^c to the wire 88 and back to the generator 87.

When the switch 92 is automatically reversed the closed circuits will be from the generator 87, through wire 100, switch 92, contacts 93 and 95, wire 97 to switch arm 81, through contacts 83, 84^a, 83^b and 84^c to wires 85, 86^a, 85^b and 86^c to the electro-magnets 70, 71^a, 70^b and 71^c, as shown in Fig. 12, and thence by way of wires 91, 90^a, 91^b and 90^c to wire 88 and back to the generator.

When it is desired to energize the electro-magnets 71, 71^a, 71^b and 71^c to set all of the signal units in "Stop" position as shown in

Fig. 13, or when it is desired to energize the electro-magnets 70, 70^a, 70^b and 70^c to set all of the units in "Go" position, as shown in Fig. 14, the switch 80 is opened and either the switch 105 or the switch 106 is closed. The switches 105 and 106 are connected to the generator as by the wire 107, and the switch 105 is arranged to make contact with the contacts 108, 108^a, 108^b and 108^c, and the switch 106 is arranged to make contact with the contacts 109, 109^a, 109^b and 109^c. The contacts 108, 108^a, 108^b and 108^c are connected respectively with the wires 85, 85^a, 85^b and 85^c as by the wires 110, 110^a, 110^b and 110^c, and the contacts 109, 109^a, 109^b and 109^c are connected respectively with the wires 86, 86^a, 86^b and 86^c as by the wires 111, 111^a, 111^b and 111^c.

When, now, the switches 105 and 106 are closed respectively circuits will be closed through magnets 70, 70^a, 70^b and 70^c or through magnets 71, 71^a, 71^b and 71^c as follows: from the generator 87, through wire 107 to either switch 105 or 106 and thence through either contacts 108, 108^a, 108^b and 108^c and wires 110, 110^a, 110^b and 110^c to wires 85, 85^a, 85^b and 85^c and through the magnets 70, 70^a, 70^b and 70^c and back to the generator 87, or through contacts 109, 109^a, 109^b and 109^c, wires 111, 111^a, 111^b and 111^c, wires 86, 86^a, 86^b and 86^c and through contacts 71, 71^a, 71^b and 71^c and back to the generator as previously described.

The switch 80 and the switches 105 and 106 in the central station and controlling the various positions of the units of a traffic regulator for a point of traffic intersection, as thus described, may be arranged to simultaneously control the units of traffic regulators at several points of traffic intersection, say for example at all of the points of traffic intersection along one of the streets A shown in Fig. 4. This arrangement is shown in Fig. 7, the controlling magnets for the use of one traffic regulator being shown at C and similar controlling magnets for the units of another traffic regulator at one of the points of traffic intersection along the street A being shown at D. The connection from the wire 40 to this latter set of controlling magnets is similar to that previously described, and the contact arms 72, 72^a, 72^b and 72^c actuated by these controlling magnets are arranged to make contact at either contacts 73, 73^a, 73^b and 73^c or contacts 74, 74^a, 74^b and 74^c, as previously described.

The respective magnets of the group of controlling magnets D may be arranged in series in the circuits to the respective similar magnets of the group of controlling magnets C. For this purpose the magnets 71, 71^a, 71^b and 71^c of the group D are shown as provided with wires 115, 115^a, 115^b and 115^c and wires 116, 116^a, 116^b and 116^c

connected to the respective wires 86, 86^a, 86^b and 86^c, and the magnets 70, 70^a, 70^b and 70^c of the group D are shown as connected by wires 117, 117^a, 117^b and 117^c and 118, 118^a, 118^b and 118^c to the respective wires 85, 85^a, 85^b and 85^c. By this arrangement it will be seen that closed circuits through any of the wires 85, 85^a, 85^b and 85^c and 86, 86^a, 86^b and 86^c will cause simultaneous energizing of similar magnets of the groups C and D. It will be obvious that any number of such groups of controlling magnets for controlling the traffic regulators at any number of points of traffic intersection may be arranged in series so as to be controlled by the same switches at the central station.

Assuming that all of the traffic regulators along one of the streets A are jointly controlled from the central station, it may be found desirable to similarly jointly control all of the traffic regulators along another of the parallel streets A. This arrangement is also shown in Fig. 7, one of the switches 80 and 105 and 106 being provided for each group of traffic regulators which are jointly controlled. Thus the switches 80, 105 and 106 for one group of traffic regulators are shown at E and another group of switches are shown at F, the arms 81 of these respective switches 80 being connected to the wire 97 leading to the contact point 95 by branch wires 119 and 120 respectively, and the wire 98 leading to contact point 96 being connected to the arms 82 of these respective switches by branch wires 121 and 122, the wire 100 leading from the generator 87 to the switches 105 and 106 connecting these switches of the respective controlling units E and F. It will be obvious that as many of the controlling units, such as shown at E and F as may be found necessary, may be thus connected, the parts being so arranged that the switches of the respective units will control their respective traffic regulators.

Various changes may be made without departing from the spirit of the invention as claimed.

What is claimed is:

1. A traffic regulator for traffic crossing points comprising signaling means for the respective cross directions, each signaling means including traffic movements and traffic stopping signals, electrically controlled actuating means for the respective signals of each signaling means, a two position switch for each signaling means adapted to close a circuit through either actuating means of a signaling means, means for moving said switches to either position and in such manner as to energize or de-energize the actuating means for the traffic stopping signals of the signaling means for one of the cross directions and energizing or de-energizing the actuating means for traffic movement signals of the signaling means for the other

of the cross directions, automatic means for controlling the last means, and means independent of said switch moving means for controlling the actuating means for all of 5 the signals so that either the traffic stopping signals or the traffic movement signals are rendered visible simultaneously.

2. A traffic regulator for traffic crossing points comprising signalling means for the 10 respective cross directions, each signalling means including traffic movements and traffic stopping signals, electrically controlled actuating means for the respective signals of each signalling means, a switch having one 15 arm thereof arranged in circuits through the actuating means for traffic movement signals of the signalling means for one of the cross directions and in circuits through the actuating means for traffic stopping signals 20 of the signalling means for the other of the cross directions, and the other arm of said switch arranged in circuits through the actuating means for traffic movement signals of the signalling means for the second of 25 said cross directions and in circuits through the actuating means for traffic stopping signals of the signalling means for the first of the cross directions, and means for closing a circuit through either of said arms and the 30 circuits in which they are arranged,

3. A traffic regulator for traffic crossing points comprising signalling means for the respective cross directions, each signalling means including traffic movements and traffic 35 stopping signals, electrically controlled actuating means for the respective signals of each signalling means, a two position switch adapted to be moved from one position to the other, said switch when in one position 40 having one arm thereof arranged in circuits through the actuating means for traffic movement signals of the signalling means for one of the cross directions and in circuits through the actuating means for traffic stopping signals of the signalling means for the other of the cross directions, and the other arm of said switch arranged in circuits through the actuating means for traffic movement signals of the signalling means 45 for the second of said cross directions and in circuits through the actuating means for traffic stopping signals of the signalling means for the first of the cross directions, said switch when in its other position having 50 one arm thereof arranged in circuits through the actuating means for traffic movement signals of the signalling means for both of the cross directions, and the other arm of said switch arranged in circuits through the actuating means for traffic stopping signals of the signalling means for both of the cross directions, and means for closing circuits 55 through either of said arms when the switch is in either position.

4. A traffic regulator for traffic crossing 65 points comprising signalling means for the respective cross directions, each signalling means including traffic movements and traffic stopping signals, electrically controlled actuating means for the respective signals of each signalling means, a switch having one arm thereof arranged in circuits through the actuating means for traffic movement signals of the signalling means for both of the cross directions, and the other arm of said switch arranged in circuits through the actuating means for traffic stopping signals of the signalling means for both of the cross directions, and means for closing a circuit 70 through either of said arms.

5. A traffic regulating system comprising traffic regulators for traffic crossing points, each of said regulators comprising signals for the respective directions of travel at the traffic crossing points, means for jointly actuating certain of said signals of a regulator to one signalling position and other of said signals to a different signalling position, and means for selectively jointly actuating the signals of a regulator to any one 85 of said signalling positions, said actuating means for the respective regulators being either locally independently controlled, or a plurality of said actuating means being 90 jointly controlled from a central station.

6. A traffic regulating system comprising traffic regulators for traffic crossing points, each of said regulators comprising signals for the respective directions of travel at the traffic crossing points, means for jointly 100 actuating certain of said signals of a regulator to one signalling position and other of said signals to a different signalling position, and selective means for either jointly actuating the signals of a regulator to one signalling position, or actuating certain of said signals to one signalling position and other of said signals to a different signalling position, said actuating means for the respective regulators being either locally independently controlled, or a plurality of said actuating means being 105 jointly controlled from a central station.

7. A traffic regulating system comprising traffic regulators for traffic crossing points, each of said regulators comprising signals for the respective directions of travel at the traffic crossing points, means for jointly 115 actuating certain of said signals of a regulator to one signalling position and other of said signals to a different signalling position, means for selectively jointly actuating the signals of a regulator to any one of said signalling positions, or for actuating certain of the signals of a regulator to one signalling position and other of said signals to a different signalling position, and means 120 for actuating the signals of a regulator to 125

the opposite signalling position, said actuating means for the respective regulators being either locally independently controlled, or a plurality of said actuating means being 5 jointly controlled from a central station.

8. A traffic regulating system comprising traffic regulators for the respective traffic crossing points, each traffic regulator comprising signalling means for the respective 10 cross directions, each signalling means including traffic movement and traffic stopping signals, electrically controlled actuating means for the respective signals of each signalling means, a two position switch 15 mechanism closing circuits through said actuating means and arranged when in one position to close circuits through the actuating means for traffic movement signals of the signalling means for one of the cross 20 directions and through the actuating means for traffic stopping signals of the signalling means for the other of the cross directions, and when in the other position to close circuits through the actuating means for traffic 25 stopping signals of the signalling means for the first of the cross directions and through the actuating means for traffic movement signals of the signalling means for the other of the cross directions, means 30 for moving said switch mechanism from one position to the other, said means including a two arm switch adapted to close contacts through each arm when the switch is closed to operate the traffic regulator controlled 35 thereby in the traffic regulating system, the respective arms of said switch controlling the respective positionings of said switch

mechanism, and means for automatically closing circuits through the respective arms of the switch at intervals. 40

9. A traffic regulator for traffic crossing points comprising signalling means for the respective cross directions, each signalling means including traffic movements and traffic stopping signals, electrically controlled 45 actuating means for the respective signals of each signalling means, a two position switch for each signalling means adapted to close a circuit through either signal of a signalling means, means for moving said 50 switches to either position, said means including a two arm switch closing circuits through one arm so as to move the two position switches in opposite directions for energizing the actuating means for traffic stopping signals of the signalling means for one of the cross directions and energizing the actuating means for traffic movement signals of the signalling means for the other of the cross directions, the other arm 55 of said switch closing circuits so as to move the two position switches in reverse opposite directions for energizing the actuating means for traffic movement signals of the signalling means for the first of the cross directions and energizing the actuating 60 means for traffic stopping signals of the signalling means for the other of the cross directions, and means for automatically closing the circuits through the respective arms 65 at intervals. 70

In testimony whereof I have signed my name to this specification.

FRANK J. HUSBANDS.
